CLAIM

The ornamental design for a tumbler, as shown and described.

DESCRIPTION

The file of this patent contains at least one drawing executed in color. Copies of this patent with color drawings will be provided by the Office upon request and payment.
 FIG. 1 is a top, front, right perspective view of a first embodiment of a tumbler showing our new design;
 FIG. 2 is a front view thereof;
 FIG. 3 is a right side view thereof;
 FIG. 4 is a rear view thereof;
 FIG. 5 is a left side view thereof;
 FIG. 6 is a top view thereof;
 FIG. 7 is a bottom view thereof;
 FIG. 8 is a cross section view showing a section taken along line 8-8 of FIG. 1;

FIG. 9 is a cross section view showing a section taken along line 9-9 of FIG. 6;

FIG. 10 is a top, front, right perspective view of a second embodiment of a tumbler showing our new design;

FIG. 11 is a front view thereof;

FIG. 12 is a right side view thereof;

FIG. 13 is a rear view thereof;

FIG. 14 is a left side view thereof;

FIG. 15 is a top view thereof;

FIG. 16 is a bottom view thereof;

FIG. 17 is a cross section view showing a section taken along line 17-17 of FIG. 10;

FIG. 18 is a cross section view showing a section taken along line 18-18 of FIG. 15;

FIG. 19 is a top, front, right perspective view of a third embodiment of a tumbler showing our new design;

FIG. 20 is a front view thereof;

FIG. 21 is a right side view thereof;

FIG. 22 is a rear view thereof;

FIG. 23 is a left side view thereof;

FIG. 24 is a top view thereof;

FIG. 25 is a bottom view thereof;

FIG. 26 is a cross section view showing a section taken along line 26-26 of FIG. 19;

FIG. 27 is a cross section view showing a section taken along line 27-27 of FIG. 24;

FIG. 28 is a top, front, right perspective view of a fourth embodiment of a tumbler showing our new design;

FIG. 29 is a front view thereof;

FIG. 30 is a right side view thereof;

FIG. 31 is a rear view thereof;

FIG. 32 is a left side view thereof;

FIG. 33 is a top view thereof;

FIG. 34 is a bottom view thereof;

FIG. 35 is a cross section view showing a section taken along line 35-35 of FIG. 28;

FIG. 36 is a cross section view showing a section taken along line 36-36 of FIG. 33;

FIG. 37 is a top, front, right perspective view of a fifth embodiment of a tumbler showing our new design;

FIG. 38 is a front view thereof;

FIG. 39 is a right side view thereof;

FIG. 40 is a rear view thereof;

FIG. 41 is a left side view thereof;

FIG. 42 is a top view thereof;

FIG. 43 is a bottom view thereof;

FIG. 44 is a cross section view showing a section taken along line 44-44 of FIG. 37;

FIG. 45 is a cross section view showing a section taken along line 45-45 of FIG. 42;

FIG. 46 is a top, front, right perspective view of a sixth embodiment of a tumbler showing our new design;

FIG. 47 is a front view thereof;

FIG. 48 is a right side view thereof;

FIG. 49 is a rear view thereof;

FIG. 50 is a left side view thereof;

FIG. 51 is a top view thereof;

FIG. 52 is a bottom view thereof;

FIG. 53 is a cross section view showing a section taken along line 53-53 of FIG. 46; and,

FIG. 54 is a cross section view showing a section taken along line 54-54 of FIG. 51.

The broken lines depicting the remainder of the tumbler show features that form no part of the claimed design. The contrast in shading shown in FIGS. 1-5 and 7-9 represents

a contrast in appearance only and does not represent any particular color, material, texture or finish. The broken lines depicting the remainder of the tumbler show features that form no part of the claimed design.

UNITED STATES PATENT AND TRADEMARK OFFICE
CERTIFICATE OF CORRECTION

PATENT NO. : D918,658 S
APPLICATION NO. : 29/658675
DATED : May 11, 2021
INVENTOR(S) : Bullock et al.

Page 1 of 1

It is certified that error appears in the above-identified patent and that said Letters Patent is hereby corrected as shown below:

On the Title Page

Page 2, Column 1, Description, Lines 1-3:

Delete "The file of this patent contains at least one drawing executed in color. Copies of this patent with color drawings will be provided by the Office upon request and payment."

Page 3, Column 1, Description, Lines 2-4:

Delete "The broken lines depicting the remainder of the tumbler show features that form no part of the claimed design." and insert --The file of this patent contains at least one drawing executed in color. Copies of this patent with color drawings will be provided by the Office upon request and payment.--
